Inventor,
Attorney.

UNITED STATES PATENT OFFICE.

WILLIAM J. EDWARDS, OF MONTREAL, QUEBEC, CANADA.

BURNER.

Application filed January 21, 1922. Serial No. 530,868.

To all whom it may concern:

Be it known that I, WILLIAM J. EDWARDS, of the city of Montreal, Province of Quebec, Dominion of Canada, a subject of the King of Great Britain, have invented certain new and useful Improvements in Burners; and I do hereby declare that the following is a full, clear, and exact description thereof.

My invention relates particularly to gas torches for burning off paint and for brazing, soldering and welding certain metals; and has for its object to provide a readily controlled hot flame.

More specifically stated the invention consists of a torch including means for adjusting the flame for use to burn paint from floors and the sides of railway cars and other surfaces, and by a variation of the flame adapt it for brazing brass, steel and malleable iron, welding cast iron and closing breaks and patching holes in aluminum parts. The principal feature of my torch is a valvular bushing or sleeve the interior whereof is divided by a plug into separate chambers one for air or oxygen and the other for ordinary coal gas. For the proportioning of the air and oxygen relatively to the coal gas I employ a pipe of diminutive bore which is carried by the plug in such a manner that it communicates with the air and oxygen chamber and projects through the gas chamber with its tip protruding slightly beyond the mouth of the torch. A tip or nozzle carried slidably by the mouth of the torch presents a chamber in which the gas and air or oxygen mix, and permits of ready adjustment of the flame for the purposes just mentioned. The construction of the torch, as hereinafter set forth, permits of simultaneous adjusting of the air or oxygen and gas or the regulation of the gas alone with a steady supply of compressed air or preadjusted oxygen gas.

For full comprehension, however, of my invention reference must be had to the accompanying drawings in which similar reference characters indicate the same parts and wherein:

Figure 1 is a side elevation of my improved torch, the tip or nozzle of the burner illustrated in this figure has a relatively large outlet;

Figure 2 is a longitudinal axial sectional view, the tip or nozzle in this figure is one having a relatively small outlet;

Figure 3 is a transverse sectional view taken on line 3—3 Figure 2;

Figure 4 is a detail view of the body of my improved torch with valvular sleeve or bushing and tip or nozzle removed;

Figure 5 is a side elevation of the valvular sleeve or bushing detached;

Figure 6 is an end view thereof; and

Figure 7 is a detail elevation of the air or oxygen pipe of diminutive bore and the plug to which one end is connected.

The preferred embodiment of my invention consists of a torch comprising a tubular body portion *b* having a neck *c* of reduced diameter. The body portion contains a rotatable bushing or sleeve *d*, substantially equal in diameter to the neck *c*, and has a head *e* with a knurled edge *f* and a central port *g* communicating with the interior of the sleeve. The bushing or sleeve and the tubular body portion have registering ports *h*, *i* and *j*, *k* respectively, while a plug *l* is rigidly set within it substantially midway the length *o* thereof, dividing the same into separate chambers *m*, *m'*. The chamber *m* is a compressed air or oxygen chamber and *m'* is a coal-gas chamber. A pipe *n* of diminutive bore extends completely through the plug by which it is carried and while communicating with the chamber *m* projects through the other chamber, *m'* and protrudes slightly beyond the mouth of the body. This pipe projects compressed air or oxygen. A tip or nozzle is fitted upon the neck with a sliding connection and its mouth is contracted to an orifice *p* slightly greater in diameter than the mouth of pipe *n* but less than the diameter of the neck *c*. A modified nozzle for use to meet different requirements is indicated at *q* in Figure 1. The mouth of this modified nozzle is of larger diameter, it being slightly less than the diameter of the neck *c*. The object of the contraction of the mouths of these nozzles is to act as baffles for the gas flowing from the body of the torch around the pipe *n* and retard its flow and cause a more intimate mixture of the air or oxygen and coal-gas.

The butt of the nozzle has a slot *r* in which a screw *r'* carried by the sleeve *d* registers, thus permitting the sleeve to be rotated in either direction to a limited extent; and it prevents axial displacement of the sleeve. The rotation of the sleeve is to open or close the air or oxygen and gas ports, and the slot

is of a length to prevent complete closing of the ports thus keeping a pilot-light burning even when the sleeve is turned to closed position.

5 Operation.

When it is required to burn paint from large surfaces as floors, walls, the sides of railway cars and the like the nozzle *o* is employed and it is adjusted to position with its mouth slightly in advance of the mouth of the air pipe *n*. According to the proportion of gas used, the larger the proportion of gas the greater capacity of chamber required between the mouth of pipe *n* and the mouth of the nozzle. This chamber is where the mixture of gas and air or gas and oxygen takes place. Ordinary coal gas is supplied to the connection *k* by a flexible pipe and a compressed air supply is connected to connection *g* by a flexible pipe, while the bore *j* is plugged as indicated in Figure 1. The torch may then be used freely and the paint of these wide surfaces is rapidly removed. If desired the plug may be removed from *j* and put in *g* and the compressed air connected at *j* for convenience in handling the torch.

When brazing brass, steel and malleable iron or welding cast iron the nozzle g is used and the connection g is plugged while an oxygen gas supply controlled by a tap j^1 is connected to connection j in place of the compressed air and the connection of ordinary coal gas at k is maintained. When repairing a broken aluminum device the arrangement just described is employed, the heat being sufficient to make the edges of the break run together and be worked until united a stick of aluminum being used to fill in; or a hole may be patched by dropping aluminum heated in the same manner onto a non-combustible anvil inserted beneath the part with the hole the edges of the hole being simultaneously raised to a welding heat.

The valvular bushing or sleeve *d* is readily adjusted by the knurled head *f* and as above described the torch is adapted to have this sleeve function to either adjust the air or oxygen and gas simultaneously when the connections are at *j* and *k* or permit a free supply of the air and regulated supply of the gas as when the connection is at *g* and *h*. The use of the plug *m* dividing the interior of the valvular sleeve into separate end chambers and carrying the pipe *n* is essential to this regulation; and the fact that the plug and pipe *n* are carried by this valvular bushing or sleeve enables a simple construction to perform the functions described.

What I claim is as follows:

1. A torch consisting of a tubular body portion with a tubular neck of less diameter than the body portion, a sleeve rotatably mounted within the body portion, means

whereby the sleeve is rotated to a limited extent, a plug within the sleeve and dividing its interior into an air chamber and a gas chamber, a pipe of diminutive bore mounted within the plug and extending axially throughout the length of the tubular neck and communicating at its opposite end with the air chamber, said sleeve and body portion having registering ports communicating with the air chamber and other ports communicating with the gas chamber. 70 75

2. A torch consisting of a tubular body portion with a tubular neck of less diameter than the body portion, a sleeve rotatably mounted within the body portion, means for limiting rotation of the sleeve consisting of a projection upon the sleeve having a limited extent of movement in a slot in the body portion, means for rotating the sleeve consisting of a knurled head formed integrally with one end of the latter and extending beyond the body portion, a plug within the sleeve and dividing its interior into an air chamber and a gas chamber, a pipe of diminutive bore mounted within the plug, a port in said body portion adapted to communicate with the air chamber, a second port in said body portion adapted to communicate with the gas chamber, ports in the sleeve adapted to register with the ports in the body portion, a port in the knurled head of the sleeve in axial alignment with the air chamber, an air supply pipe adapted to be removably connected to either the port in the body portion communicating with the air chamber or the port in the knurled head, a removable plug adapted to be mounted in the air port to which the air supply pipe is not connected and a gas supply pipe adapted to be connected to the port in the body portion which communicates with the gas chamber.

3. A torch consisting of a tubular body portion with a tubular neck of less diameter than the body portion, a sleeve rotatably mounted within the body portion, means for rotating the sleeve, a plug within the sleeve dividing its interior into a pair of axially aligned chambers one of said chambers being adapted to receive a gas and located adjacent the neck and in communication therewith, a pipe of diminutive bore mounted within the plug and extending to the mouth of the neck, its opposite end being in communication with the air chamber, a gas supply pipe adapted to communicate with the gas chamber, an air supply pipe and a pair of connections for connecting the air supply pipe to the air chamber whereby the air may be admitted in an axial direction into the air chamber or any direction perpendicular to its axis.

4. A torch for the purpose set forth consisting of a tubular body portion, a valvular bushing or sleeve rotatably mounted in the 130

body portion, a plug dividing the interior of the bushing or sleeve into separate end chambers, a pipe of diminutive bore carried at one end by the plug centrally thereof and 5 extending completely therethrough and projecting through the body portion of the torch to the mouth thereof, means whereby different inflammable gaseous fluids are independently supplied to the respective chambers consisting of registering ports in the bushing or sleeve and body portion respectively and communicating with the chamber in advance of the plug, a port in the rear end of said bushing or sleeve and registering ports in the bushing or sleeve and body portion respectively and communicating with the chamber at the rear of the plug and a removable plug for the rear port and the part contiguous thereto in the body. 10 5. A torch for the purpose set forth consisting of a tubular body portion with a tubular neck of less diameter than the body portion; a tubular bushing or sleeve within the body portion and substantially equal in 15 diameter to the neck, the body portion having a slot and the bushing or sleeve carrying a projection engaging the slot, means whereby the bushing or sleeve is rotated within the limit of the slot, a plug within the bushing or sleeve and dividing it into 20 end chambers, a pipe of diminutive bore carried at one end by the plug and extending therethrough and projecting therefrom through the torch to a short distance beyond the mouth thereof, the bushing or sleeve and 25 body portion having registering ports communicating with the chamber in advance of the plug, the bushing or sleeve and body portion having registered ports communicating with the chamber in rear of the plug, 30 and the rear end of the said bushing or sleeve being open, a removable plug for one pair of the said registering ports and the open end of the bushing or sleeve, the said open end of the bushing or sleeve having a knurled 35 head, and a nozzle carried slidably by the neck of the torch and having its end constricted over the mouth of the neck to present a mixing chamber. 40

In testimony whereof I have signed my name to this specification in the presence of two witnesses.

WILLIAM J. EDWARDS.
